UNITED STATES PATENT OFFICE.

WARREN L. CLARK, OF NEW YORK, N. Y.

METHOD OF FORMING INTERCHANGEABLE SIGN LETTERS.

Application filed February 27, 1922. Serial No. 539,593.

To all whom it may concern:

Be it known that I, WARREN L. CLARK, a citizen of the United States, residing at New York city, State of New York, have invented a certain new and useful Improvement in Methods of Forming Interchangeable Sign Letters, of which the following is a full, clear, and exact description, such as will enable others skilled in the art to which it appertains to make and use the same, reference being had to the accompanying drawings, forming part of this application, in which—

My invention relates to interchangeable letter signs and consists in an improved method of forming the letter tabs to be used in such signs and in the improved product of such method.

The object of my invention is to produce a letter tab having a hooked upper edge by which the letter may be suspended and in which the letter will be accurately located so that adjacent letters on a signboard to which the tabs are applied will align with each other.

In the accompanying drawings—

Figures 1 and 2 illustrate stages in an old method of preparing such letter tabs.

Figures 3 and 4 illustrate stages in my improved method of manufacturing the tabs, the completed tab produced by each method being shown approximately in Figure 5, although it will be understood from this specification that the tabs produced by my improved method are uniformly accurate to an extent hitherto unobtainable.

In both of these methods it is customary to lithograph a large number of letters on a single sheet 1 of metal which is then enameled and baked. It may be assumed that this lithographing operation locates the letters accurately so that exact shearing of the individual tabs from the plate and the accurate forming of their hooked edges will produce letters uniformly positioned in their respective tabs. In the old method illustrated in Figures 1 and 2, these tabs are formed by cutting the sheet 1 along the vertical lines 2 which are perpendicular to the bases of the letters. Each strip so formed is then inserted in a press—the first operation of which would be to shear the first tab from the strip by making a horizontal cut 5 and then form the hooked portion 4 by a suitable die operation. In this operation, the strip would be fed longitudinally

against a stop positioned so as to engage the upper end of a strip. Now it is practically impossible to set the stop exactly so that the tab will be precisely the right length and a minute departure from an exact setting of the stop while unnoticeable in the first few tabs produced would be readily apparent in the tabs cut from the lower portion of the strip as the length of these strips may include twenty-five or more tabs and the error in the stop setting becomes cumulative as successive tabs are cut from the strip.

An additional source of error arises from the fact that the thin rolled metal forming the plates possesses slight bends, creases or other inequalities in its surface which are increased in number during the successive shearing operations and the effect of which inequalities in the first tab is to vary the length of the tab and therefore the exactness of the lower edge of that tab and of the upper edge of the next tab blank 3 and the inequalities of the surface in the second tab will similarly affect the third tab blank 80 in addition to the error produced by the first tab.

Briefly, by the old method each tab hook will be formed after the blank is severed from the strip and its location relative to the letter on the tab will be dependent upon the upper edge of the blank. With my improved method I provide the sheet 7 in the same manner as has been done previously but instead of shearing the letters successively from vertical strips and separately forming a hooked portion for each tab after the blank is cut, I form my strips, by cutting along lines 8, Figure 3, in which a plurality of letters appear in a horizontal line 95 and this strip is then provided with a continuous hooked upper edge 9 after which the individual tabs are separated by respective vertical cuts 10. The number of tabs in each horizontal strip may be as high as 100 fifty without exceeding the total strip dimension of about half as many letters in a vertical strip. This is due to the fact that the width of many letters and characters is much less than their height.

While Figure 3 shows the letters of each strip as being duplicated and therefore of equal width, this is immaterial as letters of different widths may follow each other on each strip.

Whether or not these individual vertical cuts 10 are accurate is immaterial as depar-

tures of cuts 10 from the normal will not affect the positioning of the letter relatively to the hook, which positioning determines the alignment of the letters in a sign.

5 It will be understood that each horizontal strip is fed against a stop which engages its top edge similarly to the stop previously referred to as being used for the vertical strips. Any variation in the setting of this 10 stop will only affect the one strip as the gauge may be reset for each strip without unduly increasing the time of producing a given number of tabs while a repeated setting of the stop in the old method to secure 15 the same result would require an individual setting for each tab.

With the old method referred to, it is necessary to provide a separate forming die for each size of tab while with my method 20 it is the strip as a whole which is bent and only one bending die is required, the severance of the tabs from the strip being

formed by a press which operates independently of the width of the latter.

What I claim is:

1. An improved method of forming interchangeable sign letters consisting in severing a row of letters from a blank, thus producing a strip, then folding one edge of said strip and finally dividing the strip including its folded edge transversely. 30

2. An improved method of forming interchangeable letters which consists in arranging equal sized letters or characters in horizontal rows on a blank, severing said blank 35 horizontally to form strips, folding the edges of said strips at the tops of the letters or characters, then severing said strips transversely so as to locate the letters or characters centrally in their respective fields. 40

In testimony whereof I hereunto affix my signature this 14 day of February, 1922.

WARREN L. CLARK.
